S. S. SCHWAB

FIRE EXTINGUISHER

Filed Nov. 14, 1923

UNITED STATES PATENT OFFICE.

SAMUEL S. SCHWAB, OF TOLEDO, OHIO.

FIRE EXTINGUISHER.

Application filed November 14, 1923. Serial No. 674,613.

To all whom it may concern:

Be it known that I, SAMUEL S. SCHWAB, a citizen of the United States, and a resident of Toledo, in the county of Lucas and 5 State of Ohio, have invented a new and useful Fire Extinguisher, which invention is fully set forth in the following specification.

My invention has for its object to provide 10 a combined steam and fire-extinguishing liquid distributor whereby the combined fire-extinguishing effects of the steam and liquid may be produced in a room, the steam operating to heat and spray the fire-extinguishing liquid into all parts of the room.

My invention has for its object other features and advantages which will appear from the following description and upon examination of the drawings.

20 The invention may be contained in structures, having details that vary. To illustrate a practical application of the invention, I have selected one of such structures and shall describe it hereinafter. The structure selected is shown in the accompanying drawings.

Figure 1 of the drawings illustrates a top view of the apparatus. Fig. 2 illustrates a sectional view taken on the line 2—2 indicated in Fig. 1.

A source of steam supply is connected to the apparatus by pipe 1, in which is located an opening valve 2 for permitting steam to enter the apparatus. The valve 2 controls 35 the supply of steam to the pipe 3 which extends through a container 4. The container 4 is supported by means of suitable brackets 5 that may be located on a wall or other supporting structure.

40 The container 4 is filled with a fire-extinguishing solution, or liquid, such as carbon tetrachloride. To fill the container 4 the threaded plug 6 may be removed from a suitable opening and the liquid inserted in the container.

45 A siphon 7 is located in container 4 and is formed of a pair of pipes 8 and 9. They are connected together by a U 10. The pipe 8 extends to near the bottom of the container, while pipe 9 extends 50 through the bottom to the sprayer 11, the

bend in the U being located slightly above the level of the liquid in the container 4 to prevent the flow of the liquid from the container through the siphon 7.

The sprayer 11 is formed of a cone-shaped nozzle 12 that is located in front of elbow 13 which is secured to the lower end of the pipe 3 at a point below the bottom of the container 4. The nozzle 12 is secured in position by means of the threaded shell 14 of the sprayer 11. This forms a chamber 15 between the nozzle 12 and the wall of the shell 14 to which the siphon 7 is connected, the lower end of the pipe 9 being provided with an elbow that is threaded into the shell 14. A suitable annular plug 16 is threaded into the shell 14 to form an outlet for the mixed vapor and steam.

When the valve 2 is opened, the steam will pass down through the pipe 3 and draw 70 the liquid from the container through the siphon 7 and distribute the mixture of the steam and liquid vapor throughout the room in which the apparatus is located. In order to secure an immediate action of the apparatus, the top of the container is connected to the pipe 3 by means of the pipe 17. This will transmit the pressure within the pipe 3 to the surface of the liquid contained within the container 4 and cause a 75 rapid movement of the liquid to the sprayer 11. The liquid, moreover, is heated by the steam that it comes in contact with, and also by the heat transmitted through the pipe 3 to the liquid in the container which increases the fire-extinguishing efficiency of the liquid. The steam in itself is a fire-extinguishing element, and, moreover, it operates to increase the efficiency of the fire-extinguishing liquid as well as cause its distribution.

I claim:

In a fire extinguishing apparatus, a container, a steam pipe connected with a source of supply of steam and extending through the container, a siphon located in the container extending through the bottom of the container, one end of the siphon terminating near the bottom of the container and within the container, and the other end terminat- 95 100

ing near the bottom of the container and on the outside of the container, a nozzle connected to said steam pipe, a shell surrounding the said nozzle, the siphon connected to the said shell, the said shell having a ring forming an annular opening about the end of the nozzle for the said shell, the said ring extending a short dis-

tance beyond the said nozzle and forming a spraying and suction means for drawing 10 the material from the container, means for connecting the steam pipe with the top of the container.

In testimony whereof I have hereunto signed my name to this specification.

SAMUEL S. SCHWAB.
